SPRING ASSEMBLY FOR UPHOLSTERY

Fred A. Nachman, Jr., Chicago, Ill., assignor to
 Nachman Spring-Filled Corporation, Chicago,
 Ill., a corporation of Illinois

Application May 9, 1936, Serial No. 78,750

3 Claims. (Cl. 5—353)

The invention relates to the type of spring assemblies for upholstery, wherein each of the component springs is maintained out of contact with the next adjacent spring or springs by interposing fabric walls between contiguous springs and wherein said fabric walls cooperate with top and bottom walls, to which they are secured, to provide rows of cells, each of which may be said to be individual as to each spring.

10 Spring assemblies of the type referred to are illustrated, respectively, in Letters Patent to L. A. Suekoff No. 1,411,227 and in the Suekoff Patent No. 1,793,724, the present invention being applicable to both of said types of spring assemblies 15 and practically all other fabric encased spring assemblies known to the art.

The object of the present invention is to provide means which will act to prevent the component springs of a spring assembly of the types 20 mentioned from crowding together and becoming overlapped under the influence of lateral pressure exerted against the ends of the spring assembly as in crowding the same into a cushion cover, or the like, by means of a conventional 25 mattress stuffing machine.

A further object of the invention is to provide means for the purpose set forth which are flat and very resilient and will overlap the terminal coils of contiguous rows of springs of an 30 assembly for affording additional support for the padding disposed between the cushion cover and the top and bottom surfaces of the assembly.

A suitable embodiment of the invention is illustrated in the accompanying drawing, wherein

35 Fig. 1 is a perspective view of a fabric encased spring assembly equipped with devices made in accordance with the present invention.

Fig. 2 is a plan view of the same showing the device of the present invention secured in place by means of stitching.

40 Fig. 3 is a view similar to Fig. 2 showing the device of my invention secured in place by means of hog-nose rings or equivalent devices.

In the instance illustrated, the spring assembly 45 is substantially of the type illustrated in the L. A. Suekoff Patent No. 1,411,227, wherein a casing comprising top, bottom and peripheral walls, is equipped with partition walls extending laterally and longitudinally of the casing and 50 which are secured to said top and bottom walls by means of stitch chains 2 and 3, respectively. The casing is thus equipped with individual cells into which the springs 4 are introduced as particularly illustrated and described in said Letters Patent No. 1,411,227.

In accordance with the present invention, I mount upon either or both the top and bottom walls of the fabric casing or casings (such as are illustrated in Letters Patent No. 1,793,724) the strips 5 of wire bent to zig-zag form, so that its convolutions lie in a single plane, said strips 5 being composed of a relatively small gauge and very resilient wire.

Preferably, the convolutions of the strips 5 are varied in width at different points in the lengths of said strips so that said strips become wider along alternate portions of their lengths than at other portions thereof. The purpose of the increased widths of the strips 5 along different portions of their lengths is to cause said 10 wider portions to overlap and be supported upon the terminal coils of contiguous springs of the assembly, thus to avoid having the said springs turn on their own longitudinal axes and become noticeable to the occupant of a seat cushion containing the spring assembly. The said 15 wider portions of the strips 5 serve also to afford a firm support for padding and relieve the fabric top walls of the casings of some of the stress 20 due to their support of said padding and load 25 upon the latter.

The length of each strip 5 is substantially equal to the length of a row of springs 4 of the assembly less one of the springs of said row. Thus, in the instance illustrated, the springs 30 4 are arranged in parallel rows and each row contains six of said springs disposed practically side by side. In the instance illustrated, therefore, the length of each strip 5 will be substantially equal to five times the diameter of one of the component springs of the assembly and will overlap the terminal springs of the two contiguous rows at the points at which the springs 35 of said rows are most closely contiguous to each other. Between their terminals said strips 5 will 40 overlap the remaining springs of said two rows thereof.

Preferably, only one of said strips 5 is used for each two rows of springs of the assembly. In the instance illustrated, there are six rows of 45 springs 4 and, therefore, three of said strips 5 are shown to be mounted upon the assembly.

Also, preferably, as shown in Fig. 2, the terminal ends of each of the strips 5 are secured to the terminal springs of the two rows of the latter overlapped by said strip by means of the hog nose rings 6 or any other suitable means. Between their ends said strips 5 are secured, preferably, to each pair of opposed springs of the contiguous rows thereof overlapped by said strip 50 55

5 by means of stitching 7 which engages one of the strips 5 at a point substantially midway between its side edges and at a point where a lateral portion of the strip 5 overlaps or rests 5 upon the most closely contiguous opposed portions of a pair of springs, as at the point 8 where the stitch cord is knotted to said strip 5 and the portions of the springs next adjacent thereto. From said point 8 the stitching is passed 10 or looped consecutively about the succeeding pairs of springs and the portions of the strip lying nearest adjacent thereto, as indicated at the several points 9, said cord being then passed over to the next succeeding strip 5 and attached similarly to the succeeding points 9 in the opposite direction from the stitching of the first-mentioned strip, and thence across to the last of said strips 5, the other end of said cord being knotted at the point 10.

20 As illustrated in Fig. 3, hog nose rings 11 may be used in place of the stitching at the points 8, 9 and 10, respectively.

It will be obvious, of course, that under the influence of load on the seat cushion equipped with the spring assembly of this invention, the strips 25 5 will flex readily and because of the fact that said strips are capable of being elongated and contracted to some extent, they afford a very efficient means for accomplishing the purpose 30 for which they are intended, as hereinbefore set forth.

While I have illustrated the preferred form of the strips 5 in the accompanying drawing, it will be obvious, of course, that the exact form of 35 said strips may be changed and varied without departing from the invention as defined in the appended claims.

I claim as my invention:

1. In a spring assembly consisting of fabric 40 encased upholstery springs wherein the component springs are initially and normally maintained in predetermined relative positions by the walls of said casing, a supplementary means for maintaining said springs in said predetermined relative positions comprising a series of resilient wires bent to flat substantially zig-zag form and presenting relatively thin, flat and flexible stay 45 formations disposed upon the fabric casing material covering the tops of said springs, said stay formations being spaced from and in substantially parallel relation to each other and each thereof positioned to overlap the springs of two contiguous rows thereof said stay formations equipped with terminal ring formations, and stitching extending through and engaged at one 50 end with a ring formation of one of said stay formations and with casing fabric and confined

springs at points in the latter contiguous to said ring formation successively to points, therein overlying points in the terminals of pairs of confined springs, around the latter and said stay formation, thence to the other terminal ring formation, through and about the latter and terminals of a pair of springs contiguous to said last-named ring formation, thence across the space between said last-named ring formation of one stay formation to the nearest adjacent 10 ring formation of the next adjacent stay formation and thence successively attaching said second stay formation to said fabric and confined springs as in the first-named stay formation, said stitching being continued as above set forth to terminate in the last in line of the ring formations of the last stay formation of the series. 15

2. In a spring assembly consisting of fabric encased upholstery springs wherein the component springs are initially and normally maintained in predetermined relative positions by the walls of said casing, a supplementary means for maintaining said springs in said predetermined relative positions comprising a series of resilient wires bent to flat substantially zig-zag form and presenting relatively thin flat and flexible stay 20 formations disposed upon the fabric casing material covering the tops of said springs, said stay formations being spaced from and in substantially parallel relation to each other and each thereof positioned to overlap the springs of two contiguous rows thereof, said stay formations equipped with terminal ring formations, and stitching extending longitudinally and transversely of and engaged with the ring formations 25 of said several stay formations and with points between the ends thereof and with casing fabric and contiguous points in two springs at each point of attachment of said stitching with said stay 30 formations. 40

3. In a spring assembly composed of a plurality of parallel rows of upholstery springs disposed side by side wherein each spring is disposed and confined in a fabric cell, a plurality of resilient flat members each composed of wire bent 45 to zig-zag form and varying in width at different points in their lengths, disposed over the meeting terminal coil portions of the springs of contiguous rows and in overlapping relation to said springs and in substantially parallel relation to each other, and fastening means engaging said wires at their ends and at points between their ends and each thereof extending through the fabric casing and around the coils of two of the springs 50 of the assembly at the meeting points of said coils. 55
